UNITED STATES PATENT OFFICE.

JOHN W. BAER, OF DANVERS, AND ERNEST YOUNG, OF LYNN, MASSACHUSETTS,
ASSIGNORS TO UNITED SHOE MACHINERY COMPANY, OF PATERSON, NEW
JERSEY, A CORPORATION OF NEW JERSEY.

FASTENER FOR BUTTON-SHOES.

1,187,882.

Specification of Letters Patent. Patented June 20, 1916.

Application filed July 23, 1915. Serial No. 41,531.

To all whom it may concern:

Be it known that we, JOHN W. BAER and ERNEST YOUNG, citizens of the United States, residing at Danvers, in the county 5 of Essex and State of Massachusetts, and Lynn, in the county of Essex and State of Massachusetts, respectively, have invented certain Improvements in Fasteners for Button-Shoes, of which the following description, in connection with the accompanying drawings, is a specification, like reference characters on the drawings indicating like parts in the several figures.

This invention relates to fastening devices for holding the flaps of button shoes in proper relative position while the upper is being operated upon, as during the lasting and subsequent operations. It has been the practice to button the shoe by hand, 20 and, after the shoe has been lasted, to unbutton the shoe by a pull on the buttonhole flap. The upper, when the shoe has been lasted, is held in close conformity to the last and under tension and it frequently 25 happens that the force of the pull necessary to unbutton the shoe tears or distorts the buttonholes and sometimes pulls off the buttons.

The fastening device of our invention is 30 designed to obviate the necessity of hand buttoning and unbuttoning and provides a fastener which will hold the button and buttonhole flaps in proper relative position during the various operations on the shoe, 35 and which may be readily applied and removed.

One feature of the invention resides in the construction by which the button and buttonhole gripping elements are arranged 40 on a curve corresponding substantially with the curve of the buttons and buttonholes of a shoe upper. Such a construction greatly facilitates the application of the fastener to the shoe and the maintenance of proper 45 relative position of the parts.

Another feature of the invention resides in certain novel means arranged to coöperate with the buttonhole flap to hold the buttonhole gripping means against accidental disengagement. The fastener is also 50 constructed to permit variable spacing of the button and buttonhole gripping means to accommodate the fastener to different

spacings of the buttons and buttonholes of a shoe upper.

To this end, our device, in the embodiment selected for illustration herein, comprises a plurality of fasteners spaced apart and each comprising what may be termed generically, button and buttonhole "grips" 60 and which specifically take the form of clasps for the buttons and adjacent upwardly projecting hooks designed for insertion through adjacent buttonholes to engage the edges thereof. The series of fasteners are so constructed that they may be, and preferably are, formed from a single piece of metal, such as a single length of wire bent to shape. The wire connections between the fasteners are bent to curve the 70 fasteners so that they present a curvilinear arrangement of button and buttonhole grips corresponding substantially with the curve of the buttons and buttonholes of a shoe upper. These connections are of flexible 75 material, so that the series of fasteners may be variably spaced to accommodate them to variance in the spacing of the buttons and buttonholes and incidentally, to the accompanying slight variance in the curvature of the buttons and buttonholes.

That feature of the invention which relates to the means for preventing accidental disengagement of the buttonhole gripping means consists in the embodiment selected 85 for illustration, in extending the wire from at least one and preferably both terminal fasteners to form hooks to engage over the adjacent edge of the buttonhole flap to prevent buckling of the flap edge which tends 90 to lift the buttonhole edge from the buttonhole gripping means. This is desirable because of the tendency of the buttonhole flap to buckle during handling of the upper prior to the application of the last. It is 95 to be understood, however, that the fastener of the present invention may be used to advantage without the flap edge hold-down hooks, although this combination, as above stated, is a desirable one.

In the accompanying drawings illustrating a preferable embodiment of the invention, Figure 1 is a view in elevation of a shoe upper mounted upon a last at the beginning of the lasting operation, the fastener of the present invention being applied 105

thereto; Fig. 2 is a plan view of the fastener on an enlarged scale; and Fig. 3 is a transverse section through the shoe upper, showing the engagement of the fastener therewith.

In these drawings, 2 designates the button flap of the upper and 4 the buttonhole flap, to which the fastener of this invention is applied. This fastener in the embodiment selected for illustration is formed from a single length of wire, having one end doubled and bent to form a flap edge engaging hook 6, the wire being extended from this hook and bent to form a plurality of clasps 8, the inner ends of which are restricted and substantially closed, the outer ends of the clasps being joined and bent upwardly and inwardly, the upper ends being turned outwardly, to form hooks 10 adapted to extend through the buttonholes to engage the edge thereof and preferably to overlie slightly the edge when the upper is under tension, with the edge of the buttonhole engaging below the upper outward turned edges of the hooks, as indicated in Fig. 3. The upper engaging portion of each hook will be positioned substantially centrally above the button engaged by the adjacent clasp (see Fig. 3), so that when the fastener is applied, the buttonhole flap will be held in the position relative to the button flap that these parts will assume when actually buttoned for the button eye is attached substantially centrally of the button and will engage the edge of the buttonhole. The strands of wire 14 connecting the series of button clasps and buttonhole hooks (and consequently the whole wire frame forming the fastener), are bent to curve the series of clasps and hooks so as to present a curvilinear arrangement of button and buttonhole grips conforming substantially to the curvature of the buttons and buttonholes of a shoe upper. These connecting strands are flexible so that the series of fasteners may be variably spaced to accommodate the device to the uppers of shoes having different spacings of buttons and buttonholes and incidentally, slight variance in the line of curvature of the buttons and buttonholes. The wire at the other end of the series of clasps and hooks is extended beyond the terminal fastener and is doubled and bent to form a second flap edge hold-down hook 12, similar to the hook 6, first described, and similarly spaced from the adjacent terminal fastener.

The fastener is applied to the upper of a button shoe by moving the fastener transversely of the button flap to insert the eyes of adjacent buttons through the restricted ends of the button clasps, these restricted ends opening outwardly, owing to the resilience of the connecting strands 14. The buttonhole flap is then brought down

upon the button flap so that the hooks 10 extend through their respective buttonholes and engage with the edges thereof, the buttonhole flap at the terminals of the series of fasteners being brought under the hold-down hooks 6 and 12, which will serve to prevent any possible disengagement of the hooks 10 from their respective buttonholes because of looseness of the buttonhole flap. To remove the fastener at the conclusion of the various operations on the shoe, the edge of the buttonhole flap is disengaged from beneath the upper flap edge hold-down hook, after which the flap edge is pulled outwardly and away from the buttonhole hooks 10 easily clearing these hooks and withdrawing from beneath the lower flap edge hold-down hook, as the buttonhole hooks are released. The fastener may then be easily withdrawn from the buttons by a lateral sliding movement.

Having thus described our invention, what we claim as new and desire to secure by Letters Patent of the United States is:

1. A fastener for holding the flaps of button shoes, comprising a button grip and a buttonhole grip, and a flap edge hold-down device connected with said fastener to extend over and beyond the outer end of the buttonhole flap.

2. Means for holding the flaps of button shoes, comprising a plurality of spaced and connected fasteners, each fastener comprising a button grip and a buttonhole grip, and a clasp connected with said fasteners and arranged to extend upwardly from beneath the flap and over and beyond its outer edge.

3. Means for holding the flaps of button shoes, comprising a plurality of spaced and connected fasteners, each fastener comprising a button grip and a buttonhole grip, with clasps connected with said fasteners adjacent the terminals of the plurality of fasteners and arranged to extend upwardly from beneath the flap and over and beyond its outer edge to hold down the edge of the buttonhole flap.

4. Means for holding the flaps of button shoes, comprising a plurality of spaced and integrally connected wire fasteners, each fastener comprising a button clasp and an integral projecting hook arranged to extend through the adjacent buttonhole, and a hook integral with one of said fasteners and arranged to engage over and hold down the outer edge of the buttonhole flap.

5. Means for holding the flaps of button shoes comprising a plurality of spaced and connected fasteners forming an integral metal structure, each fastener comprising a button grip and a buttonhole grip, with integral connections between said fasteners bent to curve said fasteners to correspond substantially with the curvilinear arrange-

ment of the buttons and buttonholes of a shoe upper and an integral clasp extending upwardly and inwardly and arranged to extend over the outer edge of the buttonhole 5 flap to hold down said flap edge.

6. Means for holding the flaps of button shoes comprising, a plurality of spaced and connected fasteners forming an integral metal structure, each fastener comprising 10 a button grip and a buttonhole grip, with integral connections between said fasteners bent to curve said fasteners to correspond substantially with the curvilinear arrangement of the buttons and buttonholes of a 15 shoe upper, said fastener connections being yielding to permit varying separation and curvilinear arrangement.

7. Means for holding the flaps of button shoes, comprising a plurality of spaced and 20 connected fasteners in the form of an integral wire frame, each fastener comprising a button clasp and a buttonhole gripping hook, the connections between the fasteners being bent to curve the frame to provide a 25 curvilinear arrangement of button clasps and buttonhole hooks corresponding substantially with the curvilinear arrangement of the buttons and buttonholes of a shoe upper.

8. Means for holding the flaps of button 30 shoes, comprising a plurality of spaced and connected fasteners in the form of an integral wire frame, each fastener comprising a button clasp and an adjacent projecting hook adapted to extend through an adjacent 35 buttonhole to engage the edge of the buttonhole, with integral connections between the fasteners bent to curve the frame to provide a curvilinear arrangement of button 40 clasps and buttonhole hooks corresponding substantially with the curvilinear arrangement of the buttons and buttonholes of a shoe upper, said wire frame at the opposite ends of the line of fasteners being formed with hooks arranged to engage over 45 and hold down the adjacent edges of the buttonhole flap of the shoe.

9. A fastener for holding one side of a shoe upper in a position in which it overlaps the other side including gripping means 50 for the superposed side and means overlying the outer edge of the superposed side for preventing buckling of said edge of said superposed side.

In testimony whereof we have signed our 55 names to this specification.

JOHN W. BAER.
ERNEST YOUNG.

Copies of this patent may be obtained for five cents each, by addressing the "Commissioner of Patents, Washington, D. C."

It is hereby certified that in Letters Patent No. 1,187,882, granted June 20, 1916, upon the application of John W. Barr, of Danvers, and Ernest Young, of Lynn, Massachusetts, for an improvement in "Fasteners for Button-Shoes," an error appears in the printed specification requiring correction as follows: Page 2, line 94, claim 1, for the word "end" read *edge*; and that the said Letters Patent should be read with this correction therein that the same may conform to the record of the case in the Patent Office

Signed and sealed this 24th day of October, A. D., 1916.

[**SEAL.**]

F. W. H. CLAY,

Acting Commissioner of Patents.
